CLAIM

The ornamental design for a portable board game assembly,
as shown and described.

DESCRIPTION

FIG. 1 is a perspective view of the portable board game assembly of the instant invention in a closed position;
FIG. 2 is a perspective view thereof in an open position, the game pieces shown in an alternate position;
FIG. 3 is a top plan view thereof in the open position;
FIG. 4 is a bottom plan view thereof in the open position;
FIG. 5 is a front elevational view thereof in the open position;
FIG. 6 is a rear elevational view thereof in the open position;
FIG. 7 is a right side elevational view thereof in the open position; and,
FIG. 8 is a left side elevational view thereof in the open position.
